CLIP

Clinton E. Marshall, New York, N. Y.

Application July 15, 1933, Serial No. 680,596

9 Claims. (Cl. 24—11)

The invention relates to clips for use in connection with fountain pen caps and like articles of manufacture; and the object of the invention is to provide a clip in the form of an elongated strip

5 fashioned to form depending boundary walls, one end of the strip terminating in a ball or other bearing member, and the depending walls at the sides of the other end of the strip extending in the form of comparatively wide mounting portions 10 cut out centrally to form pairs of prongs or lugs between which is a stop wall limiting inward movement of said end of the clip with respect to its support; a further object being to provide a clip of the class described which when attached 15 to the support will have the end wall thereof in engagement with the support to maintain firm engagement with the support and to provide the desired spring tension to the clip and preventing loosening of the clip on the support in the use 20 thereof; a further object being to provide a clip of the class described, the prongs or lugs of which are so fashioned as to permit the forcible passage of the prongs through supports composed of predetermined material; and with these and 25 other objects in view, the invention consists in a device of the class and for the purpose specified, which is simple in construction, efficient in use, and which is constructed as hereinafter described and claimed.

30 The invention is fully disclosed in the following specification, of which the accompanying drawing forms a part, in which the separate parts of my improvement are designated by suitable reference characters in each of the views, and in which:

35 Fig. 1 is a face view of a clip made according to my invention shown attached to a fountain pen cap.

Fig. 2 is a section on the line 2—2 of Fig. 1.

Fig. 3 is a partial section on the line 3—3 of 40 Fig. 1 on an enlarged scale.

Fig. 4 is a side view of the clip shown in Figs. 1 to 3, detached, and showing a slight modification; and,

45 Fig. 5 is a view similar to Fig. 3 showing a modification.

In practice, I provide a clip 10 fashioned from a strip of metal which is offset to give a predetermined contour or design on the outer face 11 of the clip and to form downwardly extending side

50 walls 12 and an end wall 13 forming a substantially channel-shaped strip terminating at its free end in a ball-shaped member 14, which when the clip is attached to a fountain pen cap or other support 15 tensionally engages the outer surface 55 of the cap at all times, the ball serving to space

the spring arm of the clip away from the cap to facilitate attachment of the fountain pen to a pocket or the like.

The side walls 12 adjacent the end wall 13 include relatively wide extensions 16 which are cut out centrally to form of each extension a pair of prongs 17 between which is a stop wall 18 disposed below the edges of the walls 12 so as to space the walls 12 from the outer surface of the cap 15 as clearly seen in Fig. 2 of the drawing. In other words, the walls 18 limit the inward movement of the attached end of the clip with respect to the support, and as seen in Fig. 2 of the drawing, the walls 18 are at a slight angle with respect to the longitudinal line of the walls 12, but as seen in Fig. 4 of the drawing, the wall 18a is arranged parallel thereto.

With the device shown in Fig. 4, the clip may be attached without engaging the wall 13 with the cap as in Fig. 2, or if desired, the clip of Fig. 4 may be mounted in the same manner as the clip shown in Fig. 2, in which event, the corner portion 18b of the walls 18a will engage the cap 15 whereas the corner portions 18c will be arranged in spaced relation thereto. In mounting the clips shown in Figs. 1 to 4 inclusive in connection with a fountain pen cap 15, the cap will be provided with four apertures 19 spaced to receive the prongs or lugs 17, and these prongs or lugs are passed through the apertures 19 and are bent over by a suitable tool to engage the inner wall of the cap as seen at 20, note Fig. 3 of the drawing.

In Fig. 5 of the drawing, I have shown a slight modification of the structure shown in Figs. 1 to 3, wherein the prongs 17a are made pointed at their ends rather than rounded so as to permit the forcible mounting of the clip into and through the wall of a cap such as the cap 15 without providing the apertures 19 therein. This result may be accomplished when using caps of predetermined material such as celluloid and like compositions and by the use of suitable tools. Aside from the structure of the prongs 17a, the clip shown in Fig. 5 is identical with the clips shown in Figs. 1 to 3 inclusive, it being understood that the pointed prongs 17a, after piercing the wall of the support in connection with which they are mounted, will be turned or riveted over to retain the clip against displacement.

It will be understood that by channeling the clip or in other words forming the depending boundary walls thereon, I provide a strong and durable spring arm construction which will maintain its spring properties and perform the desired function at all times, and obviate to a large degree

distortion of the spring arm. It will also be apparent that by using the two pairs of prongs or mounting lugs on the clip, a very rigid coupling of the clip to a support is insured and one which will prevent lateral movement or shifting of the clip in the support as well as displacement of the clip therefrom.

It will be understood that while I have shown a clip of predetermined contour and design, my invention is not limited in this respect, and various changes in and modifications of the construction herein shown and described may be made within the scope of the appended claims without departing from the spirit of my invention or sacrificing its advantages.

Having fully described my invention, what I claim as new and desire to secure by Letters Patent, is:

1. A clip of the class described comprising an elongated body of channel cross sectional form, the side corners of said channeled body when viewed from the side thereof being straight from one end portion of the body to the other, the free end of the body including a part projecting in the direction of the channeled side of the body, an end wall at the other mounting end of said body, said last named end of the body including at each side thereof, a pair of projecting prongs continuous with and extending in alignment with the side walls of the body, and a stop wall intermediate the prongs and arranged below the side edges of said body to form stops for supporting that part of the clip adjacent the prongs in spaced relation to the surface of a support.

2. A clip of the class described comprising an elongated body of channel cross sectional form, the side corners of said channeled body when viewed from the side thereof being straight from one end portion of the body to the other, the free end of the body including a part projecting in the direction of the channeled side of the body, an end wall at the other mounting end of said body, said last named end of the body including at each side thereof, a pair of projecting prongs continuous with and extending in alignment with the side walls of the body, a stop wall intermediate the prongs and arranged below the side edges of said body to form stops for supporting that part of the clip adjacent the prongs in spaced relation to the surface of a support, and the ends of said prongs being pointed to facilitate attachment to a support.

3. A clip of the character described comprising a substantially straight elongated body, an enlarged gripping member at one end of said body, the side edges and other end of said body having inwardly extending boundary walls of substantially the same thickness and depth throughout, the side walls extending substantially the full length of said body, both side walls projecting adjacent the last named end of said body, the projecting portion of said wall being fashioned to form a pair of projecting coupling prongs at each side of said body in alignment with said side walls and adapted to pass through a suitable support in mounting the clip in connection therewith.

4. A clip of the character described comprising a substantially straight elongated body, an enlarged gripping member at one end of said body, the side edges and other end of said body having inwardly extending boundary walls of substantially the same thickness and depth throughout, the side walls extending substantially the full length of said body, both side walls projecting adjacent the last named end of said body, the pro-

jecting portion of said wall being fashioned to form a pair of projecting coupling prongs at each side of said body in alignment with said side walls and adapted to pass through a suitable support in mounting the clip in connection therewith, and the projecting portions of the side walls intermediate the prongs forming stops limiting inward movement of the clip with respect to the support.

5. A clip of the character described comprising a substantially straight elongated body, an enlarged gripping member at one end of said body, the side edges and other end of said body having inwardly extending boundary walls of substantially the same thickness and depth throughout, the side walls extending substantially the full length of said body, both side walls projecting adjacent the last named end of said body, the projecting portion of said wall being fashioned to form a pair of projecting coupling prongs at each side of said body in alignment with said side walls and adapted to pass through a suitable support in mounting the clip in connection therewith, the projecting portions of the side walls intermediate the prongs forming stops limiting inward movement of the clip with respect to the support, and said stop walls being disposed angularly with respect to the edges of the boundary walls of said body.

6. The combination with the cap of a fountain pen, of a clip in the form of a substantially straight elongated body including depending side walls extending throughout the major portion of the length of said body, the side walls adjacent one end of said body projecting and the projecting portions of said walls including pairs of prongs projecting in common alignment with said side walls, one pair being disposed at each side of the clip, said prongs being passed through the cap of the fountain pen in securing the clip thereto.

7. The combination with the cap of a fountain pen, of a clip in the form of a substantially straight elongated body including depending side walls extending throughout the major portion of the length of said body, the side walls adjacent one end of said body projecting and the projecting portions of said walls including pairs of prongs projecting in common alignment with said side walls, one pair being disposed at each side of the clip, said prongs being passed through the cap of the fountain pen in securing the clip thereto, and the projecting portions of the side walls intermediate the prongs forming stops limiting the inward movement of the clip with respect to said cap.

8. The combination with the cap of a fountain pen, of a clip in the form of a substantially straight elongated body including depending side walls extending throughout the major portion of the length of said body, the side walls adjacent one end of said body projecting and the projecting portions of said walls including pairs of prongs projecting in common alignment with said side walls, one pair being disposed at each side of the clip, said prongs being passed through the cap of the fountain pen in securing the clip thereto, the projecting portions of the side walls intermediate the prongs forming stops limiting the inward movement of the clip with respect to said cap, and said stop walls being angular with respect to the edges of the side walls beyond said prongs.

9. A clip of the character described comprising a substantially straight elongated body, an enlarged gripping member at one end of said body, the side edges and other end of said body having

inwardly extending boundary walls of substantially the same thickness and depth throughout, the side walls extending substantially the full length of said body, both side walls projecting adjacent the last named end of said body, the projecting portion of said wall being fashioned to form a pair of projecting coupling prongs at each side of said body in alignment with said side wall

and adapted to pass through a suitable support in mounting the clip in connection therewith, and the upper or outer surface of said body being offset outwardly in a plurality of steps arranged longitudinally of the body to reinforce and strengthen said body.
